(57) **CLAIM**

The ornamental design for a rigid hull inflatable boat, as shown and described.

DESCRIPTION

1. Rigid hull inflatable boat

FIG. 1.1 is a front elevational view of a rigid hull inflatable boat embodying our new design;

FIG. 1.2 is a bottom plan view thereof;

FIG. 1.3 is a perspective view showing the front, bottom, and right sides thereof;

FIG. 1.4 is a perspective view showing the rear, bottom, and left sides thereof;

FIG. 1.5 is a perspective view showing the top and right sides thereof;

FIG. 1.6 is a perspective view showing the top, left, and rear sides thereof; and

FIG. 1.7 is an elevational view showing the right side thereof.

The broken lines in the reproductions illustrate portions of the rigid hull inflatable boat that form no part of the claimed design.
